GEORGE C. PFEFFER, OF FLORENCE TOWNSHIP, BURLINGTON COUNTY, NEW JERSEY,
ASSIGNOR TO WALTER WOOD, OF PHILADELPHIA, PENNSYLVANIA

AUTOMATIC CONTROL FOR CENTRIFUGAL CASTING MACHINES

Application filed June 5, 1928. Serial No. 282,966.

My invention relates to electrical apparatus for controlling the different speeds at which the mold of a centrifugal casting machine is rotated in carrying out the various 5 steps in making a casting by the centrifugal process, and has particular reference to mechanism for automatically accelerating the prime mover to effect the desired changes in speed at the proper times.

10 In the art of centrifugally casting hollow metal bodies, a metal flask lined with molding sand is placed horizontally in the casting machine, and the mold is caused to rotate at a relatively low speed, say 50 R. P. M. The 15 flask is then elevated to full inclination and subsequently depressed gradually while molten iron is poured into it, distributing itself longitudinally along the bottom of the mold. When the flask has returned to horizontal position, the spinning velocity of the mold is at once greatly increased. There is a resulting development of centrifugal forces which takes place so rapidly that to all practical purposes it appears to be instantaneous. This 20 force casts the molten metal onto the cylindrical wall of the sand-lined mold, and every part of the casting is formed at the same moment.

Heretofore it has been the common practice 25 in this art to regulate the speed of the motor which drives the flask by a controller, the latter being manually operated, or automatically operated by mechanical means which are actuated by the movement of the flask carriage 30 from one position to another. With manual control, two operators are needed, one to manipulate the controls which operate the tilting mechanism, and another to manipulate the motor speed controls. On the other hand, 35 where mechanical means are employed to automatically operate the motor controller, the machinery is necessarily bulky, a large number of moving parts are required, and the apparatus does not possess the durability 40 which is desirable in a machine which is continuously in operation.

With the foregoing in view, my invention 45 provides electrical means for automatically accelerating the motor speed as the flask is lowered from the tilted position to the hori-

zontal, and additional mechanism to enable the operator to make rapid changes from one predetermined speed to another. With the use of my invention, an unskilled operator can by manipulation of a series of centrally located push buttons perform all the steps necessary to carry out the casting operation. Supplementing these advantages are those derived from the provision of additional emergency controls which enable the operator 55 to depart from the normal sequence of operations and to effect any desired change in the speed of the motor.

The various features of novelty which characterize my invention are pointed out with 60 particularity in the detailed description which follows. For a better understanding of the invention, however, its advantages and specific objects attained with its use, reference should be had to the accompanying drawings, 65 in which I have illustrated and described a preferred embodiment of the invention.

Of the drawings:

Fig. I is a diagrammatic front view of a 70 centrifugal casting machine embodying my invention.

Fig. II is an enlarged view of a door switch which is closed when the machine is in filling position.

Fig. III is an enlarged view of a second door 80 switch which is closed when the machine is in normal or spinning position.

Fig. IV is an electrical diagram showing the operation of the motor controls.

Fig. V is a schematic diagram illustrating 85 the operation of the various contactors, shown in Fig. IV; and,

Fig. VI is a schematic diagram showing an alternative arrangement which may be used 90 in place of the armature circuit shunt shown in Fig. V.

In the drawings there is shown a centrifugal casting machine comprising generally an electric motor 1, preferably a compound-wound direct current motor, a coupling 2, and a flask 3 which is lined with a refractory mold 4. The motor 1 and a hood 5, which houses the flask 3, are mounted on a tiltable carriage 6, which is pivoted at 7, and which is inclined 100

from the horizontal position by means of a hydraulic ram 8, and depressed by gravity. At the rear of the machine there is a control panel, comprehensively designated by the numeral 9, carrying the push buttons 10, 11, 12 and 13, the shunt field rheostat 33, the slow-down rheostat 32 and the armature shunt rheostat 34. On the base of the carriage 6, near its fulcrum point 7, there is a bracket 16 for operating the door switch 17 which is conveniently located on a floor beam 18. The door switch 17 is of a common type, having a spring actuated knob 19, normally retained in downward position, but which is carried upward by the bracket 16 when the carriage 6 is inclined to its maximum elevation. In the horizontal or spinning position, the switch 17 is held open by its spring, whereas in the inclined or filling position the switch 17 is closed by its contact with the bracket 16.

On the floor beam 18 there is an additional door switch 20, near the charging end of the machine, which is operated by a hinged lever 21. It likewise carries a spring actuated knob 22 which is normally held in the downward position by the weight 23, but which upon the elevation of the carriage 6 and the consequent release of the weight 23 is caused to rise. The weight 23 is preferably suspended from a drum 24 on the tilting carriage 6 by a wire 25 which passes through the lever 21 and carries a stop 26 to co-operate with the lever when the carriage is elevated or depressed. The drum 24 enables an adjustment of the length of slack wire when the carriage 6 is horizontal, thus governing the position at which the switch 20 will operate. In the horizontal position the switch 20 is closed. Upon the raising of the carriage 6 the wire 25 becomes taut, the weight 23 is released from the lever 21, and the switch 20 springs open.

The various contactors, switches and rheostats used for controlling the speed of the motor 1 are diagrammatically illustrated in Fig. IV. At the top of the drawing are shown the door switches 17 and 20, which are opened and closed by the movement of the tilting carriage 6 as hereinbefore described, together with the "stop" button 10, the "start slow" button 11, the "slow down" button 12, and the "fast" button 13. Below the control switches there is a contactor panel, comprehensively designated by the numeral 27, on which are mounted the main line contactor M, the armature shunt contactor AS, the "fast" contactor F, the shunt field relay FR, and the time relay TR. Beneath the contactor panel 27, the motor armature A is shown with its shunt field 30 and series field 31. Two rheostats 32, 33 control the resistance in the shunt field 30 and a third rheostat 34 controls the resistance in the armature shunt circuit.

The various paths which the current takes under different operating conditions are more

readily understood by reference to the schematic diagram shown in Fig. V, in which the main line conductors are represented by L' and L². In starting, the tilting carriage is in horizontal position, and consequently the door switch 20 is closed and the door switch 17 is open. The closing of the main line switch 35, preparatory to the spinning of the centrifugal casting machine, causes current to flow from L' through coil FR' and then to divide, one path being through the normally closed contact TR² of the relay TR and the other through the normally closed contact F⁴ of the "fast" contactor F, to the line L². Thus coil FR' of the shunt field relay FR is energized and its contacts FR² and FR³ are closed, so that current may pass from line L' through the branch line f' and the shunt field 30 to the branch line f², and thence, through contact FR³ and normally closed contact TR³, to line L². Accordingly the rheostats 32 and 33 are short circuited, allowing the motor 1 to have full field strength.

The machine is now ready for operation. The operator presses the "start slow" button 11, and then begins to elevate the carriage 6 to inclined position preparatory to charging the flask 5. The closing of the "start slow" button 11 permits current to pass from L' through the "start slow" switch 11 to the "stop" switch 10, which is normally closed, and then through the line m to coil M', and ultimately to line L², thus energizing coil M' of the main line contactor M, and causing its several contacts M² and M³ to close. The closure of contact M² permits current to pass from line L' through the contact M² to line a', thence through the armature A and line a² to the series field 31, and thence through resistors R⁴, R³, R² and R' to line L². A portion of the current in this circuit is shunted around the armature A and passes through the branch line y, the contact AS², and the rheostat 34. At this point, there is full resistance in the series field, no resistance in the shunt field, and a variable resistance in the armature shunt circuit. Accordingly, the motor is permitted to run at a very low speed, say 50 R. P. M., this speed, however, being capable of regulation by means of the rheostat 34.

When the carriage 6 has reached its highest position, door switch 17 has closed, and door switch 20 has opened. The closing of door switch 17 allows current to pass from L' through contact M³ to the branch line b, thence through switch 17, the normally closed "slow down" button 12 and the coil F' to line L². Thus the coil F' is energized, causing contactor F to operate, closing its contacts F² and F³ and opening its contact F⁴. No change in the motor speed occurs, the operation of contactor F being merely preparatory to the automatic acceleration of the motor on the downward movement of the carriage 6.

After the flask or mold 5 has been charged, the carriage is lowered to horizontal position. Door switch 17 opens immediately, but there is no affect upon the circuit because contactor F continues to be energized by current flowing from L' through the contact M³, the branch line b, the contact F³, the "slow down" switch 12, and the coil F' to the line L².

Just before the carriage 6 reaches the horizontal position, and at a predetermined point dependent upon the adjustment of the drum 24, the door switch 20 closes. This closes a circuit from L' through the contact M³, the line b and the contact F³ to the coil AS' and thence through the switch 20, the contacts F² and FR³ to line L².

Thus coil AS' of the armature shunt contactor AS is energized producing three different effects: First, the normally closed contact AS² is opened, permitting full current to pass through the armature A; secondly, contact AS³ is closed so that the coil TR' of the time relay TR is energized and resistors R⁴, R³, R² and R' in the armature and series field 31 are short circuited; and, thirdly, contact TR², which is normally closed, is opened so that the coil FR' is no longer energized, and the contacts FR² and FR³ are opened, thereby inserting the resistance of the field rheostat 33 in series with the shunt field 30. Accordingly, at this point there is no resistance in the armature A and series field 31, there is full current through the armature A, and there is a variable resistance 33 in the shunt field 30.

This condition causes a very rapid acceleration of the motor, its speed being determined by the setting of the rheostat 33 and preferably attaining about 1200 R. P. M. This very high speed centrifugally disperses the molten metal in the flask 5 so that it forms a hollow cylindrical body on the wall of the sand-lined mold. The pipe having formed and having begun to cool, the speed of the motor may be reduced. For this purpose the "slow down" button 12 is pressed by the operator, causing the circuit through line d and coil F' to open, which in turn closes contact F⁴ and again energizes the coil FR'. The resulting operation of contactor FR closes contact FR² and inserts the slow down rheostat 32 in parallel with the field rheostat 33, thus reducing the speed by a predetermined amount dependent upon the setting of the "slow down" rheostat. The rheostat 32 is preferably set so that a "slow down" speed of about 900 R. P. M. is attained.

If, at any time while the carriage 6 is in horizontal position and the switch 17 is of necessity open, the operator desires to obtain full motor speed, he has simply to press the "fast" button 13 to obtain this result. The closure of the "fast" switch short circuits the door switch 17, and permits current to pass through the coil F' and hence to operate the "fast" contactor F, causing the same effect

as the automatic acceleration which is had when the carriage returns from inclined to spinning position. The "fast" button eliminates the necessity of going through the entire sequence of operations, and is particularly useful when testing the apparatus or when it is desirable, in the course of normal operation, to slow down and to speed up again.

To stop the machine at any time, regardless of the position of the various contactors the "stop" button 10 is employed. This is a normally closed switch which when opened breaks the circuit to the coil M' of the main line contactor M, and hence opens contact M² which in turn breaks the circuit from the main line L' to the armature A and stops the motor 1.

In Fig. VI of the drawings, I have shown a modification of my invention, illustrating an alternative method of reducing the armature voltage for running the motor 1 at very low speeds. For this purpose I employ a separate low voltage generator G, and I add to the armature shunt contactor AS an additional contact AS⁴, which is normally open, but which closes when the coil AS' is energized. With this arrangement, the operation is substantially similar to that described. When the "start slow" button 11 is pressed operating the main line contactor M, the contact M² is closed, and current from the generator G passes through the normally closed contact AS² and the contact M² to the armature A; thence through the rheostat 34 back to the generator G. The motor 1 is caused to run at a very low speed which can be varied by the rheostat 34. When the door switch 20 closes operating contactor AS, the contact AS² is opened breaking the low voltage circuit from the generator G, and the contact AS⁴ is closed, allowing current from the line L' to pass through the armature A to the line L². It will be apparent that the same changes in speed may be acquired with the modified device as with the apparatus previously described, and that the use of a low voltage generator makes it possible to run the motor 1 at speeds far below its normal slow speed. While the generator G is illustrated as a separate unit, it is preferably a part of a motor-generator set, the motor of which derives its current from lines L' and L² and which is set in motion by the closing of the main switch 35.

It will be readily apparent that the position of the various rheostats for obtaining the desired changes in speed in the course of making a casting may be determined by experimentation, and once determined, the rheostats need not ordinarily be tampered with, for the operator can, by the use of the control buttons, perform all the necessary operations. The use of control buttons, rather than other manually operated electri-

cal devices effects a great saving in time and enables an unskilled operator to tend the casting machine with ease. Furthermore, the door switches 17 and 20, which are automatically operated by the movement of the carriage, not only relieve the operator at a time when he is engaged with the tilting controls, but also act as safety devices as they prevent any fast running of the machine while the 10 mold is being charged, and thus save many castings from defective manufacture.

While I have described my invention with some particularity, I desire it to be understood that changes may be made in the form 15 of the apparatus disclosed without departing from the spirit of my invention; that electrical means, other than those specifically described for regulating the motor speed, can be substituted with equal effectiveness, as will 20 be apparent to those skilled in the art; and that certain features of the invention may sometimes be used with advantage without a corresponding use of other features.

Having thus described my invention, what 25 I claim as new and desire to secure by Letters Patent, is:

1. In a centrifugal casting machine comprising a tiltable rotary mold, an electric motor for rotating the same, and means for 30 elevating and depressing said mold; electric means for causing the motor to run at a comparatively low speed, supplemental means to rapidly accelerate the speed of the motor, a switch actuated by the elevation of the mold 35 to prepare said supplemental means for operation, and a second switch actuated by the depression of the mold to operate said supplemental means whereby the mere elevation and depression of the mold causes automatic 40 acceleration of the motor.

2. In a centrifugal casting machine comprising a tiltable rotary mold, an electric motor for driving the mold, and means for elevating and depressing the mold; a series 45 of electric contactors and resistors co-operating with the field circuits of said motor to cause it to normally run at a comparatively low speed, a pair of switches, one actuated by the elevation of the mold and the other actuated by its depression, and supplemental electric means for causing rapid acceleration of 50 the motor, said means co-operating with the switches aforesaid so that the elevation and subsequent depression of the mold automatically accelerates the motor.

3. In a centrifugal casting machine comprising a tiltable rotary mold normally retained in horizontal position, an electric motor for driving the mold, and means for elevating 60 and depressing said mold; an electric circuit for causing the motor to run at a comparatively low speed when the mold is either in horizontal or inclined position, a pair of switches, one actuated by elevation and the other actuated by the depression of the mold,

and a supplemental electric circuit for causing rapid acceleration of the motor, said supplemental circuit being energized upon the sequential operation of the switches aforesaid.

4. In a centrifugal casting machine comprising a tiltable rotary mold normally retained in horizontal position, a motor for rotating the mold, and means for elevating and depressing said mold, an electric circuit for causing the motor to run at a very low speed when the mold is either in horizontal or inclined position, a switch actuated by the elevation of the mold, a second switch actuated by the depression of the mold, supplemental electrical means for causing rapid acceleration of the motor, said means being set in operation by the successive operation of the switches aforesaid, and means for short circuiting the first mentioned switch whereby the motor speed may be accelerated without the mold being tilted.

5. In combination with a centrifugal casting machine comprising a tiltable rotary mold, a motor for rotating the same, and means for elevating and depressing said mold; a switch operated by the depression of the mold, electrical means co-operating with the switch aforesaid to automatically accelerate the speed of the motor when the switch is operated, additional electrical means for causing the motor to run at a predetermined speed slower than the normal accelerated speed, and a push button control for setting said latter means in operation.

6. In combination with a centrifugal casting machine comprising a tiltable rotary mold, a compound motor for rotating the same, and means for elevating and depressing said mold; a switch operated by the depression of the mold, and electrical means co-operating with the said switch to automatically and simultaneously increase the armature voltage, increase the series field strength, and decrease the shunt field strength whereby the motor is caused to run at a greatly accelerated speed.

7. In combination with a centrifugal casting machine comprising a tiltable rotary mold, a motor for rotating the mold, and means for elevating and depressing the mold; a switch actuated by the depression of the mold from inclined position, an electric circuit for causing the motor to run at a very low predetermined speed, a second electric circuit co-operating with said switch for causing the motor to automatically accelerate to a predetermined speed, a third electric circuit for causing the motor to slow down to a predetermined speed greater than low speed and less than accelerated speed, and a series of push button controls for operating each of said circuits.

8. In combination with a centrifugal casting machine comprising a tiltable rotary mold, a motor for rotating said mold, and

means for elevating and depressing the mold; a switch actuated by the depression of the mold from inclined position, a low voltage generator for causing the motor to run at a very low predetermined speed, a high voltage line leading to said motor, and electrical means cooperating with the switch aforesaid to cut out the low voltage generator and to cut in the high voltage line when the switch is actuated, whereby the speed of the motor is greatly accelerated.

In testimony whereof, I have hereunto signed my name at Florence, New Jersey this 31st day of May, 1928.

15 GEORGE C. PFEFFER.
